(57) **CLAIM**

The ornamental design for a notebook computer protective case as shown and described.

DESCRIPTION

FIG. 1 is a front, left and bottom perspective view of a notebook computer protective case, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 2; and,

FIG. 10 is another rear, right and bottom perspective view of the notebook computer protective case in another state.

The broken lines shown in the drawings are included for the purpose of illustrating portions of the notebook computer protective case that form no part of the claimed design. In addition, the dot-dash broken lines in FIGS. 2 and 9 depict the boundaries of the enlargements that form no part of the claimed design.
